UNITED STATES PATENT OFFICE

ROBERT L. HAM, OF BOSTON, MASSACHUSETTS, ASSIGNOR TO SUMMIT THREAD COMPANY, OF EAST HAMPTON, CONNECTICUT, A CORPORATION OF MAINE

SEWING-MACHINE SHUTTLE

Application filed November 12, 1928. Serial No. 318,640.

This invention relates to a shuttle having a bobbin chamber adapted to contain a headless bobbin composed of a cop tube and a thread mass universally wound thereon, the ends of the bobbin being formed entirely by the ends of the thread mass and tube, no heads covering the ends of the thread mass being provided as component parts of the bobbin.

10 The chief object of the invention is to provide a shuttle having simple means for centrally confining a headless bobbin in the bobbin chamber and permitting such rotation of the bobbin as may be required by 15 the call of the stitch-forming mechanism for thread, without permitting objectionably loose or free rotation.

Another object is to permit convenient inspection of the thread mass at any time, so 20 that an operator may readily learn when replenishment is required.

Other objects will hereinafter appear.

Of the accompanying drawings forming a part of this specification—

25 Figure 1 is a side view looking toward the inner side of a shuttle embodying the invention.

Figure 2 is an enlarged section on line 2—2 of Figure 1, the bobbin chamber being closed.

30 Figure 3 is a view similar to Figure 2, showing the bobbin chamber opened, and indicating by dotted and full lines the operation of securing the disks hereinafter described to the body members of the shuttle.

35 Figure 4 is a view similar to Figure 2, omitting the spring hereinafter described.

Figure 5 shows in section a headless bobbin.

40 Figure 6 is a section on line 6—6 of Figure 3, and a plan view of parts below said line.

Figure 7 is a side view of one of the disks shown by Figures 1, 3 and 4.

45 Figure 8 is a section on line 8—8 of Figure 7.

Figure 9 is a view similar to Figure 7, showing a modification.

The same reference characters indicate the same parts in all of the figures.

50 The headless bobbin shown separately by

Figure 4, is composed wholly of a cop tube 12, and a thread mass 13, universally wound thereon, the thread mass being compressed to impart to its ends the crowning or bulging form shown by Figure 4.

55 The shuttle comprises body members 14 and 15, which are preferably members of the body of the well known Singer IM shuttle, said members being hinged together at 16, so that the body is adapted to be opened, as shown by Figure 3, to receive the bobbin, and closed, as shown by Figure 2, to confine the bobbin.

The member 14 is provided with the usual 65 spring bar 17, fixed at one end to the member 14, and bearing yieldingly at its opposite end on a portion of the member 15, the bar being adapted to hold the members 14 and 15 either closed together or separated.

The body members are provided with coinciding circular openings 18, collectively forming the divided circular wall of the bobbin chamber, and inwardly projecting flanges 19, forming narrow annular seats at opposite ends of the chamber.

75 The shuttle is characterized by two smooth surfaced heads 20, which are normally flat and resiliently flexible, the material of the heads being preferably transparent sheet celluloid, which has suitable resilient flexibility 80 and is adapted by its transparency to permit inspection of the thread mass of a bobbin confined in the chamber, and by the smoothness of its surfaces to permit a regulated rotation of the bobbin. The heads are preferably 85 discoidal, as shown by Figure 6, and the diameter of each is somewhat greater than that of the openings 18, so that when the heads are pressed into said openings, their peripheries are frictionally engaged with the 90 chamber wall formed by the openings, to prevent rotation and displacement of the heads and impart thereto a crowning form.

The heads are first placed on the inner sides of the members 14 and 15, as shown 95 by dotted lines in Figure 3, and are then forced into the openings 18, as shown by full lines. This operation frictionally engages the peripheries of the heads with the circular walls of the openings 18, and im- 100

parts a crowning or concavo-convex form to the heads. The heads are provided with central bosses 21, adapted to enter the ends of the cop tube 12, to centralize and permit rotation of the bobbin.

It will now be seen that the heads may be quickly and conveniently engaged with the body members of the shuttle in position to bear on the ends of the bobbin. The smooth surfaces of the heads, contacting with the ends of the bobbin and conforming closely thereto, permit a regulated rotation of the bobbin when thread is being withdrawn therefrom and prevent undesirably free rotation of the bobbin. A shuttle of this type is usually provided with a pressing spring 22, attached at 23 to the body member 14, and having a free end projecting into the bobbin chamber, and adapted to exert pressure on the inner end of a bobbin in the chamber, and press the outer end of the bobbin against the outer flange 19, on the member 15, the bobbin usually having heads secured to its ends, and constituting component parts of the bobbin.

The flexibility of the heads 20 is such that the pressure of the spring 22 may be transmitted through the central portion of the inner head 20, to the bobbin, the said head being inwardly flexed by the spring, so that the two heads exert the desired regulated pressure on the two ends of the bobbin.

When the bobbin is of minimum length, the inner head may be slightly spaced from the inner flange 19, as shown by Figure 2, the outer head being seated on the outer flange.

If the bobbin is of maximum length, each of the heads 20 may be seated on a flange 19, and the spring 22 may be omitted, as shown by Figure 4. I prefer, however, to employ the spring 22, because of liability of slight variations in the length of different bobbins, these variations being compensated for by the spring.

It will be seen that the heads 20 of resiliently flexible material, such as sheet celluloid, may be made very thin, so that the headless bobbin may have a greater yardage of thread than is possible when the bobbin includes heads as component parts thereof, such heads occupying space in the bobbin chamber which in the improved shuttle contains thread.

The bosses 21 have convex surfaces projecting into the ends of the cop tube 12, and sloping from the inner surfaces of the heads, so that in case a portion of the thread drops on the marginal portion of the inner head 60 and is drawn between said head and the thread mass 13, such portion may pass entirely across the inner head and the boss thereon, without being obstructed or jammed between the head and the mass.

Portions of the heads may be cut away, as

indicated by Figure 9, so that their peripheries are not continuous circles.

I claim:

A shuttle for use with a ready-wound headless bobbin, having crowning ends and composed of a cop tube and a thread wound thereon, said shuttle comprising relatively movable body members having coinciding openings collectively forming the divided wall of a circular bobbin chamber and an annular inwardly projecting flanges forming annular seats at opposite ends of said chamber, one member being movable relative to the other to open and close the chamber, the shuttle being characterized by smooth, resiliently flexible, transparent heads, adapted to confine a bobbin in the chamber and contact yieldably with the ends of the bobbin, so that the bobbin is rotatable when confined between the heads, its rotation being yieldingly opposed thereby, said heads being frictionally engaged with the chamber wall to prevent rotation and displacement of the heads, and impart thereto a crowning form, the heads being provided with central, convex, opposed, struck-out portions adapted to enter the ends of the cop tube to centralize and permit rotation of the bobbin, a spring presser fixed to one of the body members and adapted to exert inward pressure on the head 95 engaged with said member and inwardly flex the central portion of said head to increase its pressure on the bobbin.

In testimony whereof I have affixed my signature.

ROBERT L. HAM.
